FLUID-OPERATED RAPID TRAVERSE MECH-
ANISM FOR WINDING STRAND MATERIALRichard F. Dyer, Kingsport, Tenn., assignor to
Eastman Kodak Company, Rochester, N. Y.,
a corporation of New Jersey

Application March 13, 1952, Serial No. 276,356

13 Claims. (Cl. 242—43)

1

This invention relates to a high-speed traverse mechanism for textile yarns or the like in which yarn may be wound on suitable supports such as cones, tubes, or the like. It is particularly adapted for use with machines of the class described employing a fluid pressure operated traverse mechanism in which a yarn guide is carried by a piston oscillatable in a slotted tube. For such machines, reference may be had to the following patents: 2,548,523, Richard F. Dyer and Wendell G. Faw, granted April 10, 1951, and 2,571,694, Richard F. Dyer, granted October 16, 1951.

Such mechanisms work satisfactorily, and extremely high speeds, such as for instance 1200 oscillations per minute, can be obtained with them. There have been in the past, however, several difficulties; first, these machines have been much noisier than the slower speed mechanical traverse mechanisms as might be expected and, second, there have occasionally been difficulties in impurities, dust or dirt collecting in the pneumatic system and moving from the slotted guide tube of the piston into contact with the yarn or package of yarn being wound.

An object of the present invention is to overcome these difficulties in known apparatus. Another object is to provide a mechanism which is quiet in operation. Another object is to provide a mechanism in which the fluid pressure—preferably air—is so controlled that it cannot pass over the yarn being wound. Another object of the invention is to provide a valve system for high-speed traverse mechanisms which is self-contained and in which the incoming and outgoing air will be retained in the valve and in the inlet and outlet systems. Still another object of my invention is to provide a simple valve structure in which the noise of operation can be greatly reduced, if not entirely eliminated. A still further object of my invention is to provide a pneumatic system which can readily be muffled. Other objects will appear from the following specification, the novel features being particularly pointed out in the claims at the end thereof.

Coming now to the drawings wherein like reference characters denote like parts throughout;

Fig. 1 is a front elevation, partially in section, schematically showing the more essential parts of my improved rapid traverse operating mechanism;

Fig. 2 is a side elevation, partially in section, of the yarn guide and associated winding mechanism;

Fig. 3 is an enlarged sectional view of the right-hand valve, the parts being shown in an open

position from which position air entering the inlet may react on the valve members driving the piston to the opposite cylinder, which is shown in Fig. 4; and

Fig. 4 is an enlarged sectional view of the valve at the left-hand end of the slotted tube with the parts in their rest position excluding air from the slotted tube and in position to be struck by the piston moving in the direction shown by the arrow.

My invention comprises an improved valve system in which the fluid pressure passes through a closed path to and from the valve and is controlled by the valve to prevent the entrance of air into the slotted guide tube for the piston carrying the yarn guide. One of these valves is arranged at each end of the slotted guide tube and the valve elements are momentarily operated by the piston reaching the end of the tube to momentarily admit fluid pressure, which immediately reverses the direction of movement of the valve members so that the piston, in turn, is struck and is rapidly moved toward the opposite valve. Meanwhile, the valve remains in a closed position.

More specifically, and referring to Fig. 1, I provide a compressed air conduit 10 leading to a suitable source and having the desired pressure. In this conduit 10 there is positioned a valve 11, a pressure regulator 12, a pressure gauge 13 and a dampening chamber 14. Air passes from the dampening chamber 14 through a pipe 15, T 16 and pipe 17 which leads to the inlet opening 18 of the valve block 19. A similar pipe 17' leads from the T 16 to the inlet opening 18' of the valve block 19'. It is noted that the valve blocks 19 and 19' are identical except that one is right hand and the other is left hand and that, since all of the parts of the valve blocks are alike, they will be given the same reference characters primed.

The valve block includes an outlet opening 20 in which a pipe 21 leads from this opening to an outlet pipe 22 which may be led past a plurality of machines if desired so that the pipe 23 may pass the exhaust air into a muffler 24 which may be arranged outside of the building housing this mechanism or in any suitable place. Valve block 19 includes an exhaust air outlet 20' which is connected into the exhaust line 22.

Between the valve blocks 19 and 19', there is a tubular guide 25 slotted at 26 to receive a piston 27. This piston carries a yarn guide 28 which passes through the slot 26 so that, when the piston reciprocates through the tube, the yarn guide will be reciprocated.

Fig. 1 shows the valve block 19 with the inlet

valve member 31 and outlet valve member 30 in a closed position, that is, valve member 31 by means of its face 32 lying against the shoulder 33 prevents air entering the inlet from entering the slideway 34 in which the spool-like valve member 30 may slide. Also, in this view, the spool member by resting against the shoulder 35 prevents air from reaching the open end of the tubular member 25. At the same time, one of the flanges 36 lies partially over the outlet 20 and, consequently, any air between the valve elements 31 and 30 can escape through the outlet 20. This view shows the normal position of these parts.

Assuming that the piston 27 is moving rapidly in the direction shown by the arrow in Fig. 1, this piston 27 may move until the end 37 strikes the valve element 30, this element then being moved to the right with reference to Figs. 1 and 3 and, in so doing, engaging part 38 projecting from the flange 32 of valve element 31 moving it in its tubular guideway 39, this guideway being formed in the end 40 of the valve block. Valve element 31 is further provided with a flat 40 so that air will not be entrapped in the tubular slideway 39 and so that valve element 31 may rapidly move to the position shown in Fig. 3 in which air is free to enter through the air entrance 18. When this occurs, the air pressure immediately acts on exhaust valve 30 moving it to the left, this valve element immediately striking or shoving the piston 27 rapidly to the left so that it will slide freely to the left through the slotted tube 25. The valve 30 moves to the left until stopped by face 35 in which position outlet passage 20 is opened and the high pressure air is free to exhaust causing a rapid decrease in pressure on the front face of the inlet valve 31. High pressure air remains on the back side of valve 31, however, and forces the valve closed against valve seat 33. Thus, the yarn guide element 28 which is carried by the piston 27 will be driven rapidly to the left and the piston will continue to slide as shown in Fig. 4 so that movement slightly beyond the position shown in Fig. 4 and in the direction shown by the arrow will cause the left-hand valve to move through the same cycle as above described for the right-hand valve.

These actions take place with extreme rapidity so that the yarn guide is oscillated back and forth.

In selecting the materials for the inlet and outlet valves, it has been found advantageous to use materials having a high coefficient of restitution, for example, certain plastics such as, for instance, nylon (which is believed to be a trade name for plastics of the type disclosed in Patent 2,071,250, Carothers, February 6, 1937). Nylon is very desirable because of its self-lubricating qualities and because of its resiliency. Of course, any suitable material may be used for this purpose. Such a plastic, however, appears to require no lubrication and, since textile yarns may readily be soiled, such materials have distinct advantages. In addition, they are somewhat quieter than most metals would be used in the same manner.

In the above-mentioned Dyer and Dyer and Faw patents, a number of different specific forms of traverse mechanisms are shown and any desirable type may be used. However, in Fig. 2 it will be noticed that the yarn guide 28 carried by the piston 27 projects from the slot 26 so that it will be moved axially of the slotted tube 25. The yarn strand Y is therefore, moved back and forth over an idler roll 50 carried on a suitable

support 51 so that as the yarn Y is wound on a suitable support 51, such as a cone, tube, or the like, a package 52 will be formed with the yarn Y distributed back and forth over the length of the package. The support 50 may be rotated by a pulley 53, belt 54 and a pulley 55 driven by any suitable source of power. While this forms one suitable means for winding the yarn into a final package, it is to be understood that any suitable winding mechanism may be employed.

While the operation of my improved form of fluid-operated yarn guide carrier has been described above, it should be noted that the path of the fluid pressure—preferably pneumatic—is a closed one in that the compressed air flowing through the entrance 18 moves valve member 31 and with it valve member 30 to the left until the left-hand flange on the valve member 30 strikes the shoulder 35 as the piston 27 is impelled in a leftward direction through the slotted tube 25. This left-hand flange of the valve member 30 at all times prevents compressed air from entering the tube 25. The right-hand flange, in the position shown in Fig. 3, shuts off the air outlet 20 but this, of course, occurs only momentarily because air entering the inlet 18 will drive the two valve elements to their Fig. 1 position in which the flange 33 is contacted by the valve element 31, thereby cutting off compressed air from the slideway 34 and from the valve element 30. This operation, of course, takes place quite rapidly but it will be readily seen that at all times the entrance of air from the valve block 19 and into the tube 25 is prevented. Since the exhaust air passes from the outlet 20, it may be conducted through suitable pipes to a muffler 24 so that the noise of operation is greatly reduced, if not entirely eliminated, by the construction described above.

A rotating support as used herein is intended to cover cones, tubes, reels, or other supports, on which yarn or other strand material or the like may be wound into a saleable package.

While the fluid guide control construction has been described herein as particularly suitable for use on yarn or other winding machines disclosed, for instance, in Patents 2,548,523 and 2,571,694, it is obvious that my invention may also be employed with other types of fluid control apparatus, and is not limited to the structure shown in the drawings forming a part of this specification or in the construction shown in the above-mentioned patents.

The term "yarn" as used in the specification and claims may be defined as including such a variety of strand material as is possibly wound on a machine of the type described herein.

From the above, it will be seen that there is provided a device in which the several objects of my invention are achieved and which is well adapted to meet the conditions of practical use.

As various possible embodiments may readily be made, and as various changes may be made in the embodiments set forth, it is to be understood that all the matter herein set forth or shown in the accompanying drawings is to be interpreted as illustrative only and not in a limiting sense.

Having thus described my invention, what I claim is new and desire to secure by Letters Patent of the United States is:

1. A fluid yarn guide control for a fluid operated traverse mechanism which is adapted to wind yarn on a rotating support and including a yarn guide, a piston carrying the yarn guide,

5

a slotted tube in which the piston may slide with the yarn guide extending through the slot in the tube, the fluid guide control comprising a valve block at each end of the tube, fluid pressure inlets and outlets in each valve block connected to a fluid pressure line and an exhaust line, said valve blocks each including movable means for controlling the flow of fluid pressure through the valve blocks, said means lying in the path of the piston to be actuated thereby in one direction to admit fluid pressure to pass into the valve, the means including valve elements slideable in the valve block, the fluid pressure reacting on the valve elements and piston to reverse the direction of movement thereof, the means also closing the tube to the entrance of fluid pressure.

2. A fluid yarn guide control for a fluid operated traverse mechanism which is adapted to wind yarn on a rotating support and including a yarn guide, a piston carrying the yarn guide, a slotted tube in which the piston may slide with the yarn guide extending through the slot in the tube, the fluid guide control comprising a valve block at each end of the tube, fluid pressure inlets and outlets in each valve block connected to a fluid pressure line and an exhaust line, valve members for controlling the flow of fluid pressure through the valve block, said valve members comprising an inlet valve member and an outlet valve member both slidably mounted in the valve block, one of the valve members closing the valve block from the slotted tube.

3. A rapid traverse winding apparatus for yarn comprising a rotatable spindle on which yarn may be wound, a fluid pressure operated yarn guide, a piston carrying the yarn guide, a slotted tube in which the piston may reciprocate, a valve block at each end of the slotted tube, a fluid pressure entrance and exit in the valve block connected to fluid pressure inlet and outlet lines, a muffler connected to the fluid outlet line, movable inlet and outlet valve members, one of which lies in the path of movement of the piston to be momentarily operated thereby to cause fluid pressure to be admitted to the valve block to reverse the movement of the valve members and to reverse the movement of the piston, the valve member lying in the path of the piston excluding fluid pressure from the slotted tube whereby fluid pressure may pass only through the valve block inlet to and out of the valve block outlet.

4. The rapid traverse winding apparatus for yarn as defined in claim 3 characterized in that each valve block includes a pair of axially arranged slideways, one larger than the other in which the valve inlet and outlet members may slide in axial alignment with the slotted tube.

5. The rapid traverse winding apparatus for yarn as defined in claim 3 characterized in that each valve block includes a pair of axially arranged slideways, one larger than the other in which the valve inlet and outlet members may slide in axial alignment with the slotted tube, the fluid pressure inlet opening into one slideway, and the fluid pressure outlet opening from the other slideway.

6. The rapid traverse winding apparatus for yarn as defined in claim 3 characterized in that each valve block includes a pair of axially arranged slideways, one larger than the other in which the valve inlet and outlet members may slide in axial alignment with the slotted tube, the fluid pressure inlet opening into one slideway, and the fluid pressure outlet opening from the other slideway, the outlet valve member hav-

6

ing an end adapted to contact with an end of the slideway adjacent the slotted tube to prevent the outlet of air from the valve block into the slotted tube.

5 7. The rapid traverse winding apparatus for yarn as defined in claim 3 characterized in that each valve block includes a pair of axially arranged slideways, one larger than the other in which the valve inlet and outlet members may slide in axial alignment with the slotted tube, the fluid pressure inlet opening into one slideway, and the fluid pressure outlet opening from the other slideway, there being shoulders between the slotted tube and the outlet member slideway and between the inlet and outlet valve member slideways to form limiting stops for the inlet and outlet valve members.

20 8. The rapid traverse winding apparatus for yarn as defined in claim 3 characterized in that each valve block includes a pair of axially arranged slideways, one larger than the other in which the valve inlet and outlet members may slide in axial alignment with the slotted tube, the fluid pressure inlet opening into one slideway, and the fluid pressure outlet opening from the other slideway, there being shoulders between the slotted tube and the outlet member slideway and between the inlet and outlet valve member slideways to form limiting stops for the inlet and outlet valve members against which the inlet and outlet valve members normally rest for excluding fluid pressure from the slotted tube, both valve members being slidable against fluid pressure momentarily when the piston strikes one slide member moving it into contact with and moving momentarily the other valve member whereby fluid pressure may be admitted to the valve to reverse movement of both slideable valve members and the piston.

35 9. In an improved fluid guide control for a fluid operated traverse mechanism which is adapted to wind yarns on a rotating support comprising a yarn guide, a piston carrying the yarn guide, a slotted tube in which the piston may move, a valve block at each end of the tube, and valve members in the guide block, the improvement which comprises one of the valves in the valve blocks operable by fluid pressure for contacting with the piston, moving the piston in a direction away from the valve block and through the tube, said piston contacting and moving the valve member in the other valve block into a position to be acted upon by fluid pressure whereupon said valve members may move in a reverse direction to drive the piston through the tube in an opposite direction, characterized in that the fluid pressure is confined in the valve blocks and is prevented from entering the slotted tube.

60 10. The improved fluid yarn guide control for a fluid operated traverse mechanism, which is adapted to wind yarns on rotatable supports, of the type defined in claim 2 characterized in that each valve includes a fluid pressure inlet and a fluid pressure exit, slideable valve members positioned for contact with each other and for controlling the fluid pressure inlet and outlet, one of the slideable valve members being positioned in the end of the path of the piston to be operated thereby and moved to a position to contact and move the fluid pressure inlet valve and to be moved by the entering fluid pressure in a reverse direction whereby the slideable valve member which may contact with the piston and which may strike the piston and drive the piston

through the tube in an opposite direction may move to a position to exclude fluid pressure from the valve block and the slotted tube.

11. A valve particularly adapted for use with a rapid traverse winding apparatus including a slotted tube, a piston carrying a winding guide projecting through the slotted tube, said valve comprising a valve block mounted on an end of the slotted tube and having an air entrance and an air outlet therein, a pair of spaced valve seats in the block, an inlet valve member normally held against one valve seat by air from the air inlet, an outlet valve member normally resting on the other valve seat to open the air outlet, the piston being adapted to engage and move the outlet valve member to a position in which the outlet is closed, whereby the outlet valve may engage and move the inlet valve member to admit air, enabling the entering air to move the inlet valve to a closed position and to move the outlet valve member to open the outlet for the escape of air so that the movement of the piston may be reversed.

12. An improvement in a rapid traverse winding apparatus for yarn comprising a rotatable winding spindle on which a yarn winding member is mounted for rotation, a pneumatically operated yarn guide mechanism positioned adjacent thereto and adapted to guide yarn uniformly back and forth along the axis of the rotating member to uniformly wind yarn on the member, the yarn guide mechanism including a piston carrying a

yarn guide, a tube in which the piston reciprocates, a slot in the tube through which the yarn guide projects from the piston, and a valve block at each end of the tube, said improvement comprising, in combination with the valve block, an air inlet and an air outlet in the valve block leading into a valve slideway in the block, an inlet valve member in the slideway adjacent the air inlet to open and close the inlet, an air outlet valve member in the slideway movable to open and close the air outlet, the piston, air outlet valve and air inlet valve being so positioned that the piston may engage and move the outlet valve member and the outlet valve member may in turn engage and move the inlet valve member, thereby reversing the direction of movement of the piston.

13. An improvement in a rapid traverse winding apparatus for yarn as defined in claim 12 characterized in that the inlet and outlet valve members are made of a material having a high coefficient of restitution.
